UNITED STATES PATENT OFFICE.

LEROY S. PFOUTS, OF CANTON, OHIO, ASSIGNOR TO THE CANTON FOUNDRY
MACHINE COMPANY, OF SAME PLACE.

DESIGN FOR A FURNACE.

SPECIFICATION forming part of Design No. 30,414, dated March 28, 1899.

Application filed February 23, 1899. Serial No. 706,596. Term of patent 14 years.

To all whom it may concern:

Be it known that I, LEROY S. PFOUTS, a citizen of the United States, residing at Canton, Stark county, Ohio, have invented and produced a new and original Design for Furnaces, of which the following is a specification.

In the accompanying drawings, Figure 1 is a side elevation of a furnace embodying my design, while Fig. 2 is a front elevation of the same.

The leading feature of the design consists in the configuration. As shown in the drawings, it consists of a base-plate Δ , with a front plate B extending upwardly therefrom. The furnace is surmounted by a radiator C , having lateral projection D . Beneath the radi-

ator there is a contracted portion E and below this an arch-shaped shell, forming a combustion-chamber F , this being provided with the ribs f . Below the arch-shaped chamber F is a ring G and below this a fire-pot H and below the fire-pot a second ring I , the ash-pot being shown at K .

I claim—

The design for a furnace herein shown and described.

In testimony whereof I affix my signature in presence of two witnesses.

LEROY S. PFOUTS.

Witnesses:

GEO. W. JAHN,
C. H. VAN HORN.
